[57] **CLAIM**

The ornamental design for a seal lock body, as shown and described.

DESCRIPTION

FIG. 1 is a front elevational view of a seal lock body, showing our new design, the rear being a mirror image and the broken-line showing of the shackle being for illustrative purposes only and forming no part of the claimed design;

FIG. 2 is a top plan view thereof;

FIG. 3 is a bottom plan view thereof;

FIG. 4 is a left side elevational view thereof, the right side being identical in appearance;

FIG. 5 is a front elevational view of an alternate embodiment thereof, the rear being identical in appearance;

FIG. 6 is a top plan view of the embodiment of FIG. 5; FIG. 7 is a bottom plan view of the embodiment of FIG. 5; and,

FIG. 8 is a left side elevational view of the embodiment of FIG. 5, the right side being identical in appearance. The opposite end view is identical to the end view shown and the opposite side view is a mirror image of the side view as shown.
